Primary Examiner — Karen S Acker(74) *Attorney, Agent, or Firm* — Baker Botts L.L.P.**CLAIM**

The ornamental design for a film with repeating surface pattern, as shown and described.

DESCRIPTION

The sole FIGURE is a top plan view of a film with repeating surface pattern showing the new design.

The stippled shading of the design represents a surface contrast. The dot dash dot perimeter line of the film with repeating surface pattern forms no part of the claimed design.
